Primary Examiner — Jonathan J Han*Assistant Examiner* — Caitlin MacKenzie Williams*(74) Attorney, Agent, or Firm* — Pryor Cashman LLP(57) **CLAIM**

The ornamental design for a shoe, as shown and described.

DESCRIPTION

FIG. 1 is a top-front perspective view of a shoe showing my new design;

FIG. 2 is a front view of the shoe;

FIG. 3 is a back view of the shoe;

FIG. 4 is a left side view of the shoe;

FIG. 5 is a right side view of the shoe;

FIG. 6 is a top view of the shoe; and,

FIG. 7 is a bottom view of the shoe.

The broken lines in the drawings depict portions of the shoe that form no part of the claimed design.
